UNITED STATES PATENT OFFICE.

FRANK J. CAPON, OF CAMDEN, NEW JERSEY.

TRIGGER GUARD.

Application filed June 24, 1925. Serial No. 39,359.

To all whom it may concern:

Be it known that I, FRANK J. CAPON, a citizen of the United States, residing at Camden, in the county of Camden and State 5 of New Jersey, have invented new and useful Improvements in Trigger Guards, of which the following is a specification.

This invention contemplates the provision of a trigger guard for firing arms, the guard 10 being so constructed and arranged with relation to the trigger to prevent the fire arm from being casually discharged by animals or the like, should the fire arm be laid upon the ground or surface, or by the trigger 15 being brought into contact with some object, while carrying the fire arm.

More specifically stated, the invention comprehends the provision of a trigger guard for fire arms which is designed to 20 cover the trigger, and including a slide which normally encloses the trigger within the guard, and which slide must be retracted by the finger before the latter can be brought into engagement with the trigger.

25 The nature and advantages of the invention will be better understood when the following detailed description is read in connection with the accompanying drawings, the invention residing in the construction, 30 combination and arrangement of parts as claimed.

In the drawings forming part of this application, like numerals of reference indicate similar parts in the several views, and 35 wherein:

Figure 1 is a side elevation of the fire arm showing the guard attached thereto.

Figure 2 is a similar view looking at the opposite side of the gun and guard.

40 Figure 3 is an enlarged sectional view through the guard showing how the slide is retracted by the finger while moving the latter in the direction of the trigger.

Figure 4 is a view taken at a right angle to 45 Figure 3.

Figure 5 is a sectional view taken on line 5-5 of Figure 3.

Figure 6 is a perspective view of the slide.

For the purpose of illustration I have 50 shown the invention used with a double barrel shot gun herein indicated generally at 10 and provided with triggers 11 and 12 respectively, although it is to be understood that a general application of the invention 55 to fire arms of any make is contemplated by the claims.

The guard is in the nature of a casing preferably of the design illustrated and adapted to be secured to the body of the gun by suitable fastening elements, the latter 60 are adapted to be passed through attaching lugs 13 shown in Figure 4. This guard casing is preferably made up in two parts, one part including a shell or casing like portion 14 of cross sectional contour shown in Figure 3, while the other part is indicated at 15, and is formed with a lip or extension 16 which lies over the finger receiving opening in the part 15. The part 15 is arranged side by side with the part 14 and is secured thereto 65 by suitable fastening elements 17 as shown in Figure 3. When the two parts are secured together, one side of the guard is curved or rounded while the other side is substantially flattened except for the lip or extension 16 70 above referred to. Carried by the part 15 are spaced parallel plates 18 which are shaped to define a track or guideway for the finger actuated slide 19, and these plates are held associated by suitable fastening elements 20 in addition to one of the fastening elements 17 above referred to. The plates 18 are provided with aligned finger receiving openings 21 which are arranged to be covered by the lip or extension 16, and these 75 openings are normally closed by the slide 19 which is normally held in the position shown in Figure 4, that is across said opening, by the spring 22. The upper and lower edges of this slide are reduced as at 23 to accommodate itself to the formation of the plates 18, which as above stated are shaped to form guides or tracks for the slides, while projecting from the latter is an apertured lug 24 to which one end of a spring 22 is connected. It is of course to be understood that the guard in its entirety will be made in right and lefts, that is to say that the finger receiving opening together with the lip 16 80 will be arranged on either side to permit of its use with either right or left handed persons.

The guard is arranged upon the gun in the manner shown in Figures 1 and 2 with the finger receiving opening at one side of the 105 guard and so positioned with relation to the lip or extension 16, that the finger of the operator must be first inserted within the lip in order to pass the finger through the openings in the plate 18. Then the slide 19 110 must be retracted against the tension of the spring 22 in order to enable the operator to

engage either of the triggers 11 and 12 respectively. By reason of this construction, it is quite obvious that when the gun is laid upon the ground, the latter cannot be casually fired or discharged by reason of animals tripping over the gun and coming in contact with the trigger or the gun fired accidentally while carrying the same by having the trigger brought in contact with other objects.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. A trigger guard for firing arms, comprising a casing adapted to cover said trigger and having a finger receiving opening therein, a curved extension overlying said opening and beneath which the finger must pass in reaching said opening, and a finger actuated slide operating in said guard and normally projected in advance of the trig-

ger, and within said extension to partly close said opening.

2. A trigger guard for fire arms comprising a casing adapted to cover said trigger and including a curved portion and a substantially flat portion having a finger receiving opening, a curved lip extending beyond said opening and beneath which the finger must pass in reaching said opening and a spring pressed finger actuated slide operating in said guard and normally projected within said lip to partly close said opening.

3. A trigger guard for fire arms, comprising a two part casing adapted to cover said trigger, one part of the casing being curved, the other part supporting a pair of spaced parallel plates having aligned finger receiving openings, a curved lip extending beyond said openings and beneath which the finger moves in reaching said opening, a finger actuated slide operating between said plates, and a spring normally holding the slide projected within said extension to partly close said openings.

In testimony whereof I affix my signature.

FRANK J. CAPON.
